DEVICE FOR MIXING FIBROUS MATERIAL
WITH BINDERS, SUCH AS PLASTER,
CEMENT, MAGNESITE, AND THE LIKEJohannes Steinert, Hanover, Germany, assignor
to Dr. Ing. e. h. Eduard Dyckerhoff, Blumenau,
near Wunstorf, GermanyApplication November 11, 1937, Serial No. 174,048
In Germany November 17, 1936

2 Claims. (Cl. 259—2)

The present invention relates to a device for mixing fibrous materials such as for example woodwool, coco fibre and asbestos with binding media such as plaster, cement, magnesite and the like in dry, fibrous or pasty form. Such mixtures are used, for example, in the manufacture of sheets for light building construction.

It is known to mix moistened, long-fibred material with cement in a machine, in which the fibres are kept in a loose state during the coating with the cement, by means of stirring forks oscillating in vertical planes, the movements of one fork preceding those of the next fork by a fraction of a turn of the driving shaft, the forks effecting their oscillatory movement around a moving turning point.

Now, it was found, that in such devices the fibrous material could be substantially fed forward only by pushing further fibrous material through the machine, inasmuch as the stirring forks did not impart to the fibrous material any forward movement at right angles to their own planes of motion. This resulted in the material accumulating in the machine, thus causing imperfect mixing, a circumstance which, especially in the case of glutinous binding media such as plaster led to much inconvenience, in addition to deterioration in the quality of the product produced.

Further, in the known device fibrous material became stuck in the bottom part of the housing between adjacent forks since this material was not moved back into the plane of motion of the forks.

The main object of the present invention is to provide an improved construction of mixing device from which these drawbacks are eliminated. This object is achieved by causing the forks of the mixer to oscillate in a plane which is inclined in relation to the vertical. The simplest way of doing this is for example to locate the inlet end of the device and consequently also the corresponding end of the crankshaft which moves the stirring forks, at a higher level than the delivery end.

In addition to obtaining a suitable staggering of the stirring forks the high speed of the crank-shaft ensures that the mixture moves forward across the forks, thus ensuring perfect mixing and at the same time a large output without overfilling the machine.

The device according to the invention is able to deal with binding media in liquid or pasty form, and it is particularly suitable for mixing fibrous material with such binders as plaster, which set

very quickly and are in the form of a heavy and glutinous paste, as the thorough mixing of the materials is effected exceedingly quickly.

A further object of the invention is to provide means for causing the material which slips down between the forks to be immediately gathered up and fed back into the plane of motion of the succeeding fork which throws it upward, thus preventing binding media from adhering to the walls of the housing, or sitting there and then being detached later and spoiling the mixture. For this purpose according to the invention a reciprocating motion is imparted to the housing relatively to the forks.

The manner in which the above mentioned and further objects of the invention are attained will become clear from the following description of the embodiment of the invention illustrated in the accompanying drawing, in which:

Figure 1 shows a transverse section of a device 20 constructed according to the invention, the section being taken on the line 1—1 of Figure 2, namely in the plane of motion of one of the forks; and

Figure 2 illustrates a longitudinal section.

The crankshaft *c*, which is driven in any suitable manner via the flywheel *a*, is mounted in an inclined position in the bearings *r*, *r'* which are attached to a suitable framework *w*. The crank-shaft *c* carries a number of forks *d* arranged in staggered formation. Each fork *d* is also controlled by a lever *l*, which is articulated at the point *u* on the fork and at the point *t* on the frame *w*, in such a way that the tips of the forks describe an ellipse-shaped curve *k*.

The housing *g* is shaped to correspond to the upward movement of the tips of the forks *d* and has on its underside the wheels *e* which run on the rails *n* of a frame *m* which forms an inclined plane.

By means of the driven crank *h* journalled at *v* between the rails *n* and by a connecting rod *f* which is articulated to the housing *g* at the point *s* a to-and-fro motion is imparted to the housing.

The fibrous material is fed into the machine in the manner indicated in Figure 2, and the binding medium, which is preferably in liquid or paste form is added to the fibrous material at the point indicated by the arrow *p*.

If liquid or pasty binders are mixed into the fibrous material it is no longer necessary to extract excess moisture by means of hydroextractors as is often the usual practice after mixing in the known machines.

When using glutinous mixing materials, such as plaster, one or two-pronged forks have been found to be particularly advantageous, as they are easy to draw out of the mixture and do not 5 impede the passage of the mixing material from one fork to another.

What I claim and desire to secure by Letters Patent of the United States is:

1. Apparatus for continuously mixing and 10 transporting fibrous materials and binders comprising a mixing trough, a frame extending adjacent to and longitudinally of said trough, a shaft supported in said frame, said shaft being offset to form crank sections, stirrers actuated

by said crank sections, said trough and said shaft being inclined.

2. Apparatus for continuously mixing and transporting fibrous materials and binders comprising a mixing trough, a frame extending adjacent to and longitudinally of said trough, a shaft supported in said frame, said shaft being offset to form crank sections, stirrers actuated by said 5 crank sections, said trough being inclined, being open at the top and on the three sides, and being shaped in correspondence with the path followed up by the stirrer tips and means to impart to said trough a reciprocative movement.

JOHANNES STEINERT.
